UNITED STATES PATENT OFFICE.

JOHN KIRSCHBAUM, OF WATERBURY, CONNECTICUT, ASSIGNOR TO WATERBURY MFG.
CO., OF WATERBURY, CONNECTICUT, A CORPORATION.

SHADE-HOLDER.

1,266,818.

Specification of Letters Patent. Patented May 21, 1918.

Application filed August 20, 1917. Serial No. 187,038.

To all whom it may concern:

Be it known that I, JOHN KIRSCHBAUM, a citizen of the United States, residing at Waterbury, in the county of New Haven 5 and State of Connecticut, have invented a new and useful Improvement in Shade-Holders; and I do hereby declare the following, when taken in connection with the accompanying drawings and the characters 10 of reference marked thereon, to be a full, clear, and exact description of the same, and which said drawings constitute part of this application, and represent, in—

Figure 1 a view in side elevation of my 15 improved shade-holder as applied to the socket of an incandescent electric lamp.

Fig. 2 a detached plan view of the shade-holder with its wire socket-grip shown in its clamping position by full lines, and in 20 its open or clearance position by broken lines.

Fig. 3 a view of the shade-holder in vertical transverse section on the line 3—3 of Fig. 2.

Fig. 4 a view of the shade-holder in front 25 elevation with its wire socket-grip removed.

Fig. 5 a plan view of one of the modified forms which my improved shade-holder may assume.

Fig. 6 a view in transverse section on the 30 line 6—6 of Fig. 5.

Fig. 7 a broken sectional view on the line 7—7 of Fig. 5.

My invention relates to an improvement 35 in that class of shade-holders particularly designed to be used in conjunction with incandescent lamp sockets, the object being to produce a simple, reliable and strong shade-holder constructed with particular 40 reference to ease of attachment to, and removal from, such a socket.

With these ends in view, my invention consists in a shade-holder having certain details of construction and combinations of 45 parts as will be hereinafter described and pointed out in the claims.

In carrying out my invention as herein shown, I employ a hinged socket-grip made of a single piece of wire bent midway of its 50 length to form a pintle 8, and two substantially semi-circular oppositely bowed grip-

ping-arms 9 terminating at their outer ends in outwardly turned finger-pieces 10 the extreme outer ends of which are curled under upon themselves. This socket-grip is hinged 55 upon the upper face of a circular sheet-metal shade-holder 11 of any approved construction, and herein shown as provided with three thumb screws 12 for the retention of the shade the lip of which is inserted into the downwardly depending skirt of the holder in the ordinary manner. For hinging the socket-grip upon the upper face of the shade-holder, the same is formed with parallel cuts 13 (Fig. 2) and the strip 14 60 embraced by the said cuts bent to form a semi-circular bearing 15 for the reception of the pintle 8 of the grip. In practice, the strap 14 is struck into the position shown by broken lines at 16 in Fig. 3 of the drawings after which one end of the wire grip is introduced. When the pintle 8 of the grip has been brought into registration with the strap, the same is struck downward to form the semi-circular bearing 15 already 65 described. When the grip is in place, its gripping-arms 9 stand directly above a depending bearing-collar 17 formed in the upper face of the shade-holder and concentric therewith. When the said arms are 70 drawn toward each other, the circular or substantially circular opening formed by them substantially corresponds to the diameter of the collar 17 aforesaid.

The finger-pieces 10 of the grip, are held 75 in their closed positions, by a pair of oppositely located upstanding retaining-hooks 18 located close to the edge of the upper face of the shade-holder at a point thereon opposite from the bearing 15 above described, 80 the opposing edges of the said hooks being beveled as at 19 and notched as at 20. As shown in Figs. 1 to 4 of the drawings, these hooks are struck up from the upper face of the shade-holder.

As shown, and preferably, the wire socket-grip will be inclined from its bearing 15 to its locking notch 20 as shown in Fig. 3, so that it will exert a downward draft upon the upper edge of the bead 21 formed near 100 the lower end of the socket 22 and thus to crowd the lower edge of the said bead down.

upon the upper face of the shade-holder at the point 23, the projecting end 24 of the socket being at this time held in the concentric collar 19 of the shade-holder.

5 In the use of my improved shade-holder, the same is applied to the lamp-socket the lower end of which is passed between the two arms of the wire socket-grip, the lower edge of the bead 21 of the socket being seated upon the upper face of the holder at the point 23 with the end 24 of the socket entered into the collar 16, by which the socket and collar are prevented from canting with respect to each other.

15 The outwardly bowed finger-pieces 10 of the socket-grip are now drawn together and entered between the retaining-hooks 18 and pushed downward between the same for engagement with the notches 20 thereof. By 20 this action the semi-circular gripping arms 9 of the socket-grip have been clasped around the socket at a point directly above the bead 21 and have seated the lower edge of the said bead firmly upon the shade-holder at the point 23, whereby the socket and shade-holder are firmly clamped together. To release the shade-holder, it is only necessary to pinch the finger-pieces 10 together so as to disengage them from the hooks 18 out of which they are then lifted and permitted to spring apart and clear the bead 21, thus permitting the shade-holder to be drawn away from the socket, or vice versa.

35 As shown in Figs. 5 and 7 of the drawings, the shade-holder is cut as at 24 to produce a leaf which is turned upon itself to form a knuckle 25 for the pintle 8 of the hinged wire socket-grip.

40 In Figs. 5 and 6 of the drawings, the upstanding retaining-hooks 26 instead of being made integral with the shade-holder as shown in Figs. 1 to 4 inclusive, are formed upon an independent base-plate 27 furnished at its ends with fingers 28 which are passed through slots 29 in the top of the shade-holder and clamped upon the inner face thereof.

I claim:

50 1. The combination with a shade-holder having a socket-receiving opening, of a yielding, socket-grip pivotally mounted upon the upper face of the said shade-holder at a point to one side of the said socket-receiving 55 opening thereof, and means for engaging with the said grip when the same is swung into its socket-holding position at which time it is placed under tension for drawing the shade-holder and socket together.

60 2. The combination with a shade-holder formed with a concentric bearing-collar; of a socket-grip hinged to the upper face of the said shade-holder and comprising two oppositely bowed arms terminating in finger-pieces, and means on the shade-holder

for being engaged by the said finger-pieces whereby the said arms are gripped upon a socket entered into the said bearing-collar of the shade-holder.

3. The combination with a shade-holder 70 having a concentric bearing-collar for the reception of the outer end of an incandescent electric lamp-socket, of a socket-grip pivotally mounted upon the upper face of the shade-holder and adapted to grip the said end of the socket, and means co-acting with the said grip at a point opposite its hinged end for securing it in its gripping adjustment. 75

4. The combination with a shade-holder 80 having a concentric bearing-collar for the reception of the outer end of an incandescent electric lamp-socket, of a socket-grip pivotally mounted upon the upper face of the shade-holder so as to substantially register 85 with the said collar, and locking means for the said grip, the said grip being inclined between its hinged and locking end for drawing the socket and shade-holder together. 90

5. The combination with an incandescent electric lamp socket provided at its outer end with a circumferential bead; of a shade-holder having a concentric bearing-collar for the reception of the outer end of the 95 said socket the bead of which rests upon the shade-holder at a point adjacent to the said collar, a socket-grip pivotally mounted upon the shade-holder and adapted to engage with the upper edge of the said bead so as 100 to force the lower edge thereof into engagement with the shade-holder, and means for holding the said socket-grip in its gripping position.

6. The combination with a shade-holder 105 having a concentric bearing-collar, of a socket-grip made from a single piece of wire, pivotally mounted upon the upper face of the shade-holder and comprising a pintle and two outwardly bowed gripping-arms 110 terminating in finger-pieces.

7. The combination with a shade-holder, of a socket-grip made from a single piece of wire, pivotally mounted upon the upper face of the said shade-holder and comprising 115 two outwardly bowed gripping-arms terminating in finger-pieces, retaining hooks upstanding from the upper face of the said shade-holder and adapted to receive the said arms between them and to be respectively 120 engaged thereby, and means mounted in the said shade-holder for the suspension of a shade therefrom.

8. The combination with an annular shade-holder having a socket-receiving 125 opening, of a yielding strap-like socket-grip pivotally mounted upon the upper face of the said shade-holder at a point to one side of the said opening and adapted to engage with the annular bead of the socket 130

when the same is entered into the said opening of the shade-holder, and means for placing the said socket-grip under tension and for holding it in its closed position, whereby
5 the said bead of the socket is drawn into engagement with the shade-holder and firmly held in such engagement.

In testimony whereof, I have signed this specification in the presence of two subscribing witnesses.

JOHN KIRSCHBAUM.
